CLAIM

The ornamental design for a container for measuring electrical characteristics, as shown and described.

DESCRIPTION

FIG. 1 is a perspective view of a first embodiment of a container for measuring electrical characteristics showing our new design;

FIG. 2 is a left side elevational view thereof; and

FIG. 3 is a cross sectional view along the line 3-3 of FIG. 2; and

FIG. 4 is a right side elevational view thereof.

FIG. 5 is a perspective view of a second embodiment of a container for measuring electrical characteristics showing our new design;

FIG. 6 is a left side elevational view thereof;

FIG. 7 is a cross sectional view along the line 7-7 of FIG. 6; and,

FIG. 8 is a right side elevational view thereof.

The even-dash broken lines showing of the container for measuring electrical characteristics are included for the purpose of illustrating unclaimed portions of the container and form no part of the claimed design. The dot-dash broken lines define the bounds of the claimed design and form no part thereof.
